Primary Examiner — Cynthia M Chin

(57) **CLAIM**

The ornamental design for a cookware handle, as shown and described.

DESCRIPTION

FIG. 1 is a perspective view of a cookware handle showing my new design;

FIG. 2 is a side view of the cookware handle of FIG. 1, the opposite side view being a mirror image thereof.

FIG. 3 is a top view of the cookware handle of FIG. 1; and, FIG. 4 is a cross-sectional view of the cookware handle of FIG. 1, taken along the lines 4—4 in FIG. 3.
